UNITED STATES PATENT OFFICE.

GEORGE CROMPTON, JR., OF WORCESTER, MASSACHUSETTS, ASSIGNOR TO ROBERT G. PRATT, OF WORCESTER, MASSACHUSETTS.

SHUTTLE-FEELING MECHANISM FOR LOOMS.

Application filed August 4, 1922. Serial No. 579,679.

To all whom it may concern:

Be it known that I, GEORGE CROMPTON, Jr., a citizen of the United States, residing at Worcester, in the county of Worcester and Commonwealth of Massachusetts, have invented a new and useful Improvement in Shuttle-Feeling Mechanism for Looms, of which the following, together with the accompanying drawings, is a specification.

19 My invention relates to shuttle feeling mechanism for looms, particularly of the "narrow ware type," in which a plurality of spaced shuttles are adapted to be driven back and forth in unison with respect to a 15 plurality of spaced groups of warp threads, in order to simultaneously weave a number of separate strips of narrow fabric, such for example, as tape or ribbon.

In my copending application, Serial No. 20 567,719, filed June 12, 1922, there is shown and described an improved shuttle changing mechanism for looms of the above described type, by means of which the shuttles may be automatically changed without interrupting the operation of the loom, when the shuttles have made a predetermined number 25 of picks, the shuttle change being brought about by a transferring mechanism adapted to eject a spent shuttle from its carrier and 30 insert a fresh shuttle in place of the same.

The object of the present invention is to provide a shuttle feeling mechanism adapted to prevent the operation of the transferring mechanism in the event that the shuttles 35 are not properly operating or "boxed," thereby effectively preventing smashing of the loom mechanism. The above, and other advantageous features of my invention will hereinafter more fully appear, reference 40 being had to the accompanying drawings, in which—

Figure 1 is a plan view of a portion of a loom provided with my improved shuttle 45 feeling mechanism, the breast beam being broken away to show the parts more clearly.

Figure 2 is a view in end elevation of the parts shown in Fig. 1, a portion of the shuttle changing mechanism being shown to enable the present invention to be clearly 50 understood.

Fig. 3 is an enlarged vertical sectional view along the line 3—3 of Fig. 2, looking in the direction of the arrows.

Fig. 4 is a perspective view showing the arrangement of my improved mechanism,

portions thereof being shown as removed from the loom in order to illustrate the arrangement more clearly.

Like reference characters refer to like parts in the different figures.

Referring first to Figs. 1 and 2, a portion of the lay of a loom is indicated at 1, and has mounted thereon a plurality of shuttle carriers 2 that are adapted to be moved back and forth in unison on race blocks 3 by means of the usual toothed rack engaging the pinions adapted to drive the carriers 2. Transferrers 4 are provided for alternate shuttle carriers 2, and each is adapted, by a downward movement, to transfer a fresh 70 shuttle 5 from a suitable holder, not shown, to a carrier 2, thereby ejecting the exhausted shuttle.

A plunger 6 is provided for the transfer 75 rer 4 and projects from the front face of the lay 1, so that movement will be imparted thereto to operate the transfer 4, should the plunger encounter an obstruction on the forward movement of the lay 1. An operating shaft 7 is mounted at the front of the loom below the breast beam, and has mounted thereon a U-shaped stop member 8 which, when in a substantially horizontal position, is in the path of movement of the plunger 6. Any desired number of stop 80 members 8 may be mounted on the operating shaft 7, each adapted to cooperate with its corresponding plunger 6, as described in the above mentioned copending application, Serial No. 567,719. In order to illustrate 85 the present invention as simply as possible, I have shown but one plunger 6, the motion of which is adapted to be transmitted to the transfer 4, but it is apparent that the turning movement of the shaft 7, can be utilized to cause any desired number of stop members 8 to be moved into operative position with respect to any desired number of plungers 6. The normal position of the 90 stop 8 is out of the path of movement of the plunger 6, as indicated in dotted lines, Fig. 2, and the shaft 7 is adapted to be turned in a clockwise direction to lift the stop 8 into its operative position, by means of an arm 9 connected to one arm 10 of a 95 bell crank lever, through a link 11.

The other arm 12 of the bell crank lever is connected to a gag 13 which is adapted to be pressed into a slot 14 provided on the periphery of a cylinder 15 by a spring 10^a act- 110

ing on the arm 10. The cylinder 15 forms a portion of a measuring device, the operation of which is fully shown and described in the above mentioned copending application, 5 the operation of the measuring device being such that the gag 13 will be received in the slot 14 after the active shuttles of the loom have made a predetermined number of picks. As the gag 13 normally rides on the periphery of the cylinder 15, it is apparent that 10 when the gag enters the slot 14, its downward movement will result in a turning movement of the operating shaft 7 in a clockwise direction, by reason of the connection of the shaft 7 to the gag 13, through the bell crank lever. The parts described thus far form no part of the present invention, and their operation is more fully described 15 in the above mentioned copending application. Enough of the mechanism has been shown and described however, to make it plain that the transfeerer 4 is adapted to be automatically operated to change a shuttle, after the loom has made a predetermined 20 number of picks, by the turning of the shaft 7 in a clockwise direction, and the resultant positioning of the stop member 8 into the path of movement of the plunger 6.

As previously set forth, it is the object of 30 the present invention to provide a shuttle feeling mechanism adapted to prevent the operation of the transfer mechanism in the event that the shuttles are not properly boxed. To this end I provide shuttle feelers 35 16 and 17, pivotally mounted on shafts 18 and 19 respectively, at opposite ends of the lay, the end of each feeler being normally maintained in the path of movement of the endmost shuttle carriers 2 by means of springs 20 and 21 respectively. When the loom is operating with the shuttles properly boxed, the feeler 16 is turned in a counterclockwise direction each time the shuttle carriers are moved to the left, while the feeler 17 is turned in a clockwise direction 45 each time the shuttle carriers 2 are moved to the right. In order to coordinate the movements of the feelers 16 and 17, the feeler 17 is connected by a flexible member 50 22 to a lever 23, pivotally mounted on a pin 24 below the feeler 16, as best shown in Fig. 4. The lever 23 is provided with a hooked portion 25, beyond its pivot pin 24, which is adapted to engage a pin 26 projecting 55 downwardly from the feeler 16, whenever movement of the feeler 17 is imparted to the lever 23 through the flexible member 22. When the hooked portion 25 engages the pin 26, it tends to turn the shuttle feeler 16 60 in a counterclockwise direction, so that the shaft 18 is always turned in the same direction whenever either shuttle feeler 16 or 17 is engaged by either endmost shuttle carrier 2.

As best shown in Figs. 3 and 4, the shaft

18 extends downwardly through the lay 1 and is provided at its lower end with an arm 27 which extends below a trigger 28. The trigger 28 is pivotally mounted between lugs 29 carried by the lay 1 and is provided with a downwardly extending heel portion 30. The trigger 28 is normally maintained in a substantially horizontal position by means of a spring 31, so that the heel portion 30 is in the path of movement of the arm 27 whenever the shaft 18 is turned in a counterclockwise direction.

As best shown in Fig. 1, a trigger slide 32 is slidably mounted in brackets 33 carried by an upright frame member 34 supporting the breast beam of the loom, not shown, and a spring 35 is adapted to yieldingly maintain the slide 32 in the direction of the trigger 28, a shoulder 32^a limiting movement of the slide 32 in the direction of the lay 1. 35 The end of the slide 32 is provided with a notch 36 which is adapted to receive the pointed end 28^a of the trigger 28, if the latter is in its horizontal position as the lay 1 moves forward. The opposite end of the 40 slide 32 is provided with a curved surface 37 which is normally in engagement with a curved surface 38 provided on an arm 39 mounted on the rock shaft 7, so that longitudinal movement of the slide 32 to the right 45 is adapted to turn the shaft 7 in a counterclockwise direction, as indicated by the arrow in Fig. 4. Having described the various parts entering into my invention, the operation thereof is as follows:

During the normal operation of the loom, and so long as the shuttles are being properly moved back and forth, the feelers 16 and 17 are adapted to be alternately engaged by the endmost shuttle carriers 2, and thereby cause a turning movement of the shaft 18 in a counterclockwise direction, each time the shuttles are moved to the right or to the left. Each time the shaft 18 is turned by either feeler 16 or 17, the arm 27 engages the heel portion 30 of the trigger 28 and moves the trigger downwardly against the action of the spring 31 into the position shown in dotted lines, Fig. 2. As the lay 1 moves forward, following 110 the depression of the trigger 28, the slide 32 is cleared by the trigger 28, and this movement is repeated on each forward beat of the lay 1, so long as the shuttles are properly moved.

If, however, at any time during the operation of the loom, the shuttles should not be properly operated, the feelers 16 and 17 will not be moved to turn the shaft 18, and consequently the trigger 28 will not be depressed. The trigger 28 will, therefore, engage with the slide 32 on the next forward movement of the lay 1, and will move it in the direction of the arm 39. If at that moment the gag 13 is riding on the surface 130

of the cylinder 15, it is obvious that the arm 39 will occupy the dotted line position and the slide 32 will not engage it. If, on the other hand, the gag 13 has been received in the slot 14, and has thereby turned the shaft 7 to bring the stop member 8 into the path of movement of the plunger 6, as shown in Fig. 4, then the surface 38 of the arm 39 will be engaged by the surface 37 of the slide 32 and the shaft 7 will be turned in a counterclockwise direction. This turning of the shaft 7 moves the stop member 8 downwardly out of the path of movement of the plunger 6, thereby preventing operation of the transerrer 4, as the lay completes its forward movement. It will be noted that the trigger 28 is adapted to engage the slide member 32 before the plunger 6 can engage the stop member 8, so there is ample time for the shaft 7 to be turned by the slide 32 to move the stop member 8 downwardly into its inoperative position.

From the foregoing, it is apparent that by my invention I have provided an improved shuttle changing mechanism for automatic woft replenishing looms of the narrow ware type which, by its action is adapted to prevent operation of the transferring mechanism in the event that the shuttles should fail to be properly operated, or boxed. While I have shown the shuttle feelers operated directly by the movement of the shuttle carriers, it is obvious that the movement of the rack rod which operates the shuttle carriers might as well be depended upon to operate the feelers. In addition, the turning movement of the shaft 7, which occurs upon failure of the shuttle feelers to be moved, might also be employed to stop the loom and to actuate some suitable device for attracting the attention of

the loom operative, in addition to rendering the transfer mechanism inoperative. Various other modifications in the arrangement of the parts entering into my invention may be made without departing from the spirit and scope thereof, and I desire that only such limitations be imposed thereon as may come within the scope of the appended claims.

I claim,

1. In a loom employing a plurality of simultaneously driven carriers containing separate shuttles, means for automatically replenishing the shuttles in said carriers, and means dependent upon the position of said carriers for controlling the functioning of the replenishing means.

2. In a loom employing a plurality of simultaneously driven carriers containing separate shuttles, means for automatically replenishing the shuttles in said carriers, and means for preventing the functioning of said replenishing means upon the failure of said carriers to be driven to a position proper for such replenishment.

3. In a shuttle feeling mechanism for looms, a plurality of simultaneously driven shuttles and a shuttle transferring mechanism, of means dependent upon the position of said shuttles for controlling the operation of said transferring mechanism.

4. In a shuttle feeling mechanism for looms, a plurality of simultaneously driven shuttles going between race blocks and a shuttle transferring mechanism, of feeler members actuated by the entering of said shuttles into their race blocks adapted to prevent the operation of said shuttle transferring mechanism upon failure of said shuttles to completely enter said blocks.

Dated this 29th day of July, 1922.

GEORGE CROMPTON, JR.
